UNITED STATES PATENT OFFICE

ARTHUR H. SAMUELSEN, OF MILWAUKEE, WISCONSIN, ASSIGNOR TO THE HEIL CO., OF MILWAUKEE, WISCONSIN, A CORPORATION OF WISCONSIN

PARTITION

Application filed August 29, 1927. Serial No. 216,251.

This invention relates to improvements in partitions for truck or wagon bodies and the like, and one of the objects of the invention is to provide a novel means of simple construction for securing a partition member to the wagon body so that the body will be divided whereby different commodities may be hauled and not permitted to mix or run together.

10 The invention contemplates a novel form of stop means on the truck or wagon body which will hold the partition in locked position when it is desired to dump only the commodity in the end section of the body, 15 and a further object of the invention is to provide means for raising the partition so as to disengage it from the stop means so that the partition may freely swing to allow the contents of the inner section to be emptied.

20 A more specific object is to provide angle brackets secured to the sides of the wagon body and corresponding clip members on the lower portion of the partition for engaging the angle brackets when in the locked position, and means for raising the partition out of engagement with the angle brackets to allow it to swing freely when the contents of the inner section are to be dumped.

25 A further object of this invention is to provide a locking means for the partition which will not become clogged up with sand or dirt which frequently occurs when such commodities are carried.

The invention consists in the novel arrangements, constructions and devices to be hereinafter described and claimed for carrying out the above stated objects as will appear from the following description of a certain preferred embodiment illustrated in 35 the accompanying drawings, wherein—

Fig. 1 is a side elevation of the partition embodying the principles of this invention in combination with a truck body, parts of the body being broken away;

45 Fig. 2 is a similar view showing the partition in the raised or open position; and

Fig. 3 is a front elevation of the partition as attached to a truck body, the body being shown in section, and parts of the partition being broken away.

Referring now to the drawing in which the same reference numerals designate the same parts in all of the views, the invention is illustrated in connection with a wagon or truck body comprising a bottom portion 6 and side portions 7. The respective sides of the body are preferably provided with horizontal flange portions 8 which form supports for bearing members 9. The bearing members 9 have journaled therein eccentric members 10 which are formed with alined apertures 11 for the insertion of a transversely extending rod 12, the rod being rigidly secured to each eccentric member, and also at one end to a lever 13.

55 A partition member 14 extending transversely across the wagon body is hingedly mounted on the rod 12, preferably by providing a plurality of vertically extending hinge members 15 riveted or otherwise secured to the partition member, the central portions of which are provided with loop portions 16 which encircle the rod 12. Angle brackets 17 secured to each side of the truck body and extending therefrom are adapted 60 to be engaged by clips 18 when the partition is in the lowered or locked position.

65 It will now be apparent from the foregoing description, assuming the parts in the position shown in Fig. 1, that when the rod is turned by the lever, the eccentric members 10 will also be turned in their respective bearings and the partition member will be raised sufficiently for the clips 18 to disengage the angle brackets 17 so that the partition may 70 swing outwardly, that is, in the direction indicated by the arrow in Fig. 2, to permit the commodity which has been held in place by the partition member to flow outwardly 75 underneath the partition. The arrangement 80

is particularly useful and convenient in connection with wagon or truck bodies adapted to be tilted so that their contents may be discharged through the rear end when in a tilted position. When so used the partition member will readily swing to open position under the weight of the load bearing against it so that the load will be quickly discharged. When the truck body is lowered, the partition member swings by gravity backwardly 85 90 95 100

against the angle bracket 17 and by turning the lever, the partition may be forced downwardly until the clip member 18 engages the angle bracket 17.

5 It will be obvious that a plurality of such partition members may be applied to a wagon or truck body if desired. The principles of the invention may also be applied to the end gate of the wagon or truck body as will 10 be obvious to those skilled in the art.

10 What I claim is:

15 In a truck body having a bottom portion and integral side walls, brackets rigidly connected directly to the side walls closely adjacent the bottom portion and extending inwardly towards each other, a partition member having forwardly projecting clips positioned to latch the partition in closed position to the upper edges of said brackets, eccentric 20 members for pivotally connecting the upper portion of the partition to the upper portions of the side walls and for bodily lifting the partition to unlatch the partition from the brackets, said bracket and clip connections 25 being located to connect the lower portions of the partition directly to the side walls of the body at points of greatest strain and above the bottom thereof, and means for turning the eccentrics.

30 In testimony whereof, I affix my signature.
ARTHUR H. SAMUELSEN.
